(57) **CLAIM**

The ornamental design for an light emitting diode module, as shown and described.

DESCRIPTION

FIG. 1 is a front view of a light emitting diode module showing our new design, the rear view being identical to the front view;

FIG. 2 is a right side view thereof, the left side view being identical to the right side view;

FIG. 3 is a top view thereof;

FIG. 4 is a bottom thereof; and,

FIG. 5 is an enlarged cross-sectional view taken along line 5-5 in FIG. 1 with the internal parts omitted.

The portion shown in double cross-hatched lines in FIG. 5 is pervious to light.
